Filed Apr. 27, 1961, Ser. No. 64,922

Term of patent 3½ years

(Cl. D91—1)

FIG. 1 is a perspective view of a water filter unit for swimming pools or the like embodying my new design, with the portions shown broken away in part to indicate indeterminate lengths.

FIG. 2 is a reduced elevation thereof as seen from the opposite side of FIG. 1 with the cord and hoses omitted for convenience of illustration only.

The dominant features of my design reside in the portions shown in full lines. The end of the motor housing not shown is plain except for the cord.

I claim:

The design for a water filter unit for swimming pools or the like, as shown and described.
